ANCHOR RAIL SHIMS

Peter C. Marinen, 3886 Grant St., Gary, Ind.
Filed Oct. 30, 1961, Ser. No. 149,486
3 Claims. (Cl. 238—327)

The subject application is a continuation-in-part of my copending application, Serial No. 87,296, filed February 6, 1961.

This invention relates to railroad rail anchor means and more particularly to supplemental means for renovating and making more effective worn out anchor means.

The primary object of my invention is to provide a shim that can be readily inserted between a rail and a partially worn or damaged anchor to renew or reestablish a firm clamping action between the rail and anchor.

A significant object of the invention is to provide a shim preferably of metal adapted for insertion between an anchor and a rail in a manner whereby to compensate for any loss or distortion of the material of the anchor resulting from excessive wear.

An important object of the invention is to provide a relatively inexpensive shim preferably constructed of resiliently flexible sheet metal which is adapted to be inserted between the anchor and the rail, when the holding or locking action of the anchor is no longer effective, thereby eliminating the necessity of replacing a rather expensive anchor per se.

Another important object of the invention is to provide a shim or anti-rattle device which is clamped or locked in position by applying a force or forces to the anchor in a direction transverse to the longitudinal axis of the rail to which the anchor is detachably connected.

A specific object of the invention is to provide a shim which is preferably constructed of sheet material having a hardness which is preferably substantially equivalent to or slightly less than that of the anchor.

A further object of the invention is to provide a novel method of applying a shim and anchor therefor to a rail.

Additional attributes of the invention reside in providing a shim and an organization which offers advantages with respect to efficiency in operation, durability, installation, and economy as to manufacture.

Other objects and advantages of the invention will become apparent after the description hereinafter set forth is considered in conjunction with the drawings annexed hereto.

In the drawings:

FIGURE 1 is a perspective view showing two conventional anchor plates mounted on a rail and provided with my improved metal shims;

FIGURE 2 is a vertical section of a rail with one of my improved shims in place between the rail and an anchor;

FIGURE 3 is a perspective view of one of a pair of corresponding shims;

FIGURE 4 is a partial vertical section of a rail showing the manner in which the shim is first manually applied to a flange of the rail;

FIGURE 5 is a partial vertical section of a rail depicting a step of a mode of applying an anchor to the rail to force the shim onto the flange;

FIGURE 6 is a partial vertical section of a rail showing the anchor in its normal connected relation with the rail, with the shim locked in an operative position;

FIGURE 7 is a vertical section taken substantially on line 7—7 of FIGURE 7 showing the areas or lines of contact between the shim, rail flange and anchor; and

FIGURE 8 is a partial vertical section of a rail illustrating the use of a shim constructed from sheet material which has a cross-sectional dimension somewhat less than that of the shim shown in FIGURE 3.

2

Referring to the drawing, numeral 5 generally designates a portion of a conventional rail having the usual head 6, intermediate web 7 and a base 8.

The rail 5 is supported upon a plurality of conventional stationary ties including the tie 9. A pair of corresponding elongate anchors or members generally designated 10 are detachably connected to the base 8 in longitudinally spaced transverse parallel positions along the length of the rail in straddling abutting relationship with respect to the vertical sides of the tie in a manner whereby to assist in stabilizing the normal upright position of the rail and substantially preventing longitudinal creepage or shifting thereof in a direction transverse to the ties.

Due to the constant travel of many trains over rails and the vibrations caused thereby, each of the anchors eventually wears, especially at the internal area or location designated by the numeral 11, and as a result it becomes loose and rattles and no longer serves its intended purpose. Factors with respect to replacing worn anchors 10 with new ones add to the overall cost of maintaining the rail system in proper condition.

The subject invention avoids replacement of a worn out anchor while still maintaining the same as effective or more effective than if it were new. To this end, I provide a shim generally designated 12, as exemplified in FIGURE 3, which may be readily manually installed between the base 8 and the worn out area or areas 11 in an anchor, thus providing a firm grip or clamp of the shim and anchor on the rail, as shown in FIGURE 1.

As exemplified in the drawing, each shim has a short upper inclined planar portion or member 13, a lower horizontal planar portion or member 14 somewhat longer than the portion 13, and a vertical planar portion or member 15 constituting a bridge joining the upper and lower portions. As evidenced in FIGURE 4, the shim is readily manually applied to one of a pair of opposed flanges 16 and 17 of the rail with the free end or edge of the upper portion of the shim engaging an upper inclined surface 18 of the flange 16 and the major surface area of the lower portion engaging the under surface of this flange or base. It will be noted that the bridge portion 15 is spaced from the edge of the flange 16. The shims are preferably constructed from resiliently flexible sheet metal strip stock having a hardness which is preferably substantially the same or somewhat softer than the hardness of the anchors so that they will flexibly conform or accommodate themselves to the flange and worn area 11. The area 11 is generally scalloped or concave and in some instances this area may be generally regular or irregular in shape.

Various forms of anchors are utilized but each of those disclosed herein preferably includes a jaw 19 for receiving the flange 16, a jaw 20 for receiving a flange 17 corresponding to the flange 16, and an elongate curvilinear bridge generally designated 21 connecting the jaws. The jaws are each substantially U-shaped in cross-section and the jaw 20 is preferably provided with a continuation forming a projection or abutment 22 which is adapted to be forcibly engaged by an elongate special lever, operably by an individual, which is utilized to selectively remove each anchor from a rail. Each of the anchors is resiliently flexible in character substantially throughout its length and may be referred to as a clamp. The jaws may also be referred to as being clamps due to their resiliently flexible gripping structure. The bridge 21 preferably includes a relatively large depending substantially U-shaped spring or portion 23 which promotes the flexibility of the anchor and offers a relatively large curved surface area for engaging the side of a tie to assist in stabilizing the position of the anchor and rail. It will be observed that the depending portion 23 on each anchor has a lower rounded extremity which is preferably some-

what wider in cross-section than at its upper extremity where legs or sides of the portion join lower portions 24 of the jaws. The portions 24 are preferably inclined to assist in imparting strength to the anchor and provide clearance so that corresponding convex surfaces 25 and 26 of each anchor will respectively engage the lower portion 14 of a shim and the under surface of the flange 17 as exemplified in FIGURE 1.

Attention is directed to the fact that while FIGURES 5 and 6 only show the jaw 19 as being provided with an internal worn area 11, it is recognized that the internal area of the jaw 20 and the edges of the flanges 16 and 17 of the rail may also wear to some extent.

Each of the anchors shown in FIGURE 1 is preferably applied and fastened to the rail by placing the anchor thereunder so that the jaw 19 receives the shim and the flange 16. A special lever (not shown) provided with a head is then connected to the anchor and engages the jaw 19 and spring 23 for forcing the anchor in a direction transverse to the length of the rail to cause the jaw 19 to press the shim onto the flange 16 to the position substantially depicted in FIGURES 2 and 5, whereupon application of additional force in a generally upward direction on the jaw 20 will cause this jaw to snap into embracing clamping relationship with the flange 17, thereby positively locking the anchor and shim in their respective operative positions with respect to one another and the rail. The abutment 22 is provided with a surface which serves to cam or pilot the jaw 22 into proper connecting relation to the rail. When the jaw 20 is being forced onto the flange 17 and finally secured thereto the material of the shim between its upper portion 13 and vertical portion 15 and forming a corner portion is pressured into conforming relationship with the area 11 and at least about the upper portion of the edge of the flange 16 as depicted in FIGURE 6. It will be noted that when the anchor is firmly secured in place through the agency of the shim, that the free end of the upper portion 13 of the shim may take an inclined spaced position relative to the inclined surface 18 of the flange and that a portion of the lower portion 14 of the shim may take an inclined spaced position relative to the under surface of the flange. It will be manifest that the shim is disposed substantially within the confines of the anchor for substantial concealment and engages the area 11 and the surface 25 over parallel longitudinal extending areas of contact or engagement at different locations and elevations. Otherwise expressed, the shim engages the area 11 and the flange 16 over an upper longitudinal area and between the surface 25 and under surface of the flange over a lower longitudinal area. The areas of contact established have proven very efficient and durable in practice.

It is to be understood that the shims may be made of different thicknesses of metal or other suitable material to accommodate anchor wear of different degrees. For example, where the wear in the jaw 19 of the anchor 10 is great, a shim of greater thickness may be used, whereas if the wear is less than that shown, a shim of less thickness, such as 26 as shown in FIGURE 8, may be used.

From the foregoing it is believed that the construction and operation of my invention may be readily understood by those skilled in the art, and it is apparent that changes may be made in the details disclosed, without departing from the spirit of the invention as expressed in the following claims.

I claim:

1. A method of applying an elongate resiliently flexible clamping member provided with a jaw at one end having an internal worn area and locking means at its opposite end and a substantially U-shaped resiliently flexible shim having a distortable corner portion to a rail having a head,

web and a pair of base flanges in which each flange has an upper longitudinally extending edge portion of a configuration different from that of said distortable corner portion of said shim, which comprises applying the shim to one of the flanges in a direction transverse to the longitudinal axis of the rail to yieldably receive said flange, placing the clamping member under the rail so that said jaw receives said one flange and substantially receives said shim within its confines, and then applying a force to said member in a direction transverse to said axis to cause said holding means to connect with the other flange to hold the member to the rail and thereby distort said distortable corner portion of said shim out of its original shape into conforming relationship with said edge portion of said one flange and said worn area of said jaw.

2. A shim for use with a railroad rail and an elongate clamp, in which the rail includes a head, web and a pair of base flanges with each flange having an inclined upper surface, a bottom surface and a substantially vertical surface defining in combination with said upper surface a longitudinally extending upper edge portion, the clamp has a jaw at one end provided with an internal worn area for location opposite said edge portion and holding means at its opposite end, and the shim is substantially U-shaped, and resiliently flexible and comprises an inclined upper planar leg, a lower planar leg and a bridge forming in combination with said upper leg a corner portion, said shim being adapted for manual disposition in receiving relation with one of said flanges so that when said clamp is applied to said rail to cause its jaw to receive said one flange and said shim and its holding means the other of said flanges, said corner portion of said shim will be distorted into conforming relationship with said edge portion of said one flange and said worn area of said jaw.

3. In combination: a railroad rail comprising a head, web and a pair of internally extending flanges at least one of which has an upper inclined planar surface, a lower horizontal surface and a substantially vertical surface defining in combination with said inclined surface an upper longitudinally extending edge portion, an elongate clamping member extending transversely under said rail and having a jaw at one end receiving said one rail flange and means at its opposite end connected to the other flange, said jaw having an internal worn area located directly opposite said upper edge portion, a substantially U-shaped resiliently flexible thin shim disposed substantially within the confines of said jaw and receiving said one flange comprising a lower horizontal planar leg, an upper planar leg and a bridge forming in combination with said upper leg an upper corner portion, said clamping member exerting forces serving to distort said corner portion of said shim out of its original shape into conforming relationship with said edge portion of said one flange and said worn area of said one jaw for firmly holding said member to said rail.
